(57) **CLAIM**

The ornamental design for a cover for a container, as shown and described.

DESCRIPTION

FIG. 1 is a top, side and front perspective view of a cover for a container showing the new design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof; and,

FIG. 6 is a bottom plan view thereof.

1 Claim, 4 Drawing Sheets
